(57) **CLAIM**

The ornamental design for a steering wheel including steering wheel for cars and steering wheel for game controllers, as shown and described.

DESCRIPTION

FIG. 1 is a front perspective view of a steering wheel including steering wheel for cars and steering wheel for game controllers, showing my new design;

FIG. 2 is a front elevation view thereof;

FIG. 3 is a rear elevation view thereof;

FIG. 4 is a top view thereof;

FIG. 5 is a bottom view thereof;

FIG. 6 is a side view thereof taken from the right of FIG. 2; and,

FIG. 7 is a side view thereof taken from the left of FIG. 2.

The drawings include elements shown in broken lines for illustrative purposes only; these elements do not form part of the claimed design.
